United States Patent Office

Des. 191,955
Patented Dec. 19, 1961

191,955

THERMOSTAT

Stephen H. Briggs, Hollywood, Calif., assignor to General Controls Co., Glendale, Calif., a corporation of California

Filed Mar. 20, 1961, Ser. No. 64,378

Term of patent 14 years

(Cl. D52—7)

FIG. 1.

FIG. 2.

FIG. 3.

FIGURE 1 is a front perspective of a thermostat, showing my new design.

FIGURE 2 is a view in elevation of one side of the same, such view being of the right hand side of the thermostat; and

FIGURE 3 is a plan view of the bottom of same.

I claim:

The ornamental design for a thermostat, as shown.
